UNITED STATES PATENT OFFICE

94,389

DESIGN FOR A WHEEL BODY

Charles Marienthal, Detroit, Mich.

Application June 15, 1934, Serial No. 52,187

Term of patent 14 years

To all whom it may concern:

Be it known that I, Charles Marienthal, a citizen of the United States of America, and a resident of Detroit, Wayne County and State of Michigan, have invented a new, original, and ornamental Design for a Wheel Body, of which the following is a specification, reference being had to the accompanying drawing.

Fig. 1 is a side elevational view of a wheel body showing my new design, and

Fig. 2 shows a sectional view taken on the line 2--2 of Figure 1.

What I claim is:

The ornamental design for a wheel body, substantially as shown.

In testimony whereof, I affix my signature.

CHARLES MARIENTHAL.
